Primary Examiner—Philip S. Hyder*Assistant Examiner*—Carol Rademaker(57) **CLAIM**

The ornamental design for a combined container and closure, as shown and described.

DESCRIPTION

FIG. 1 is a perspective view of the combined container and closure according to my new design;

FIG. 2 is an elevational view showing the front of the combined container and closure of FIG. 1;

FIG. 3 is an elevational view showing the rear of the combined container and closure of FIG. 1;

FIG. 4 is a top plan view of the combined container and closure of FIG. 1;

FIG. 5 is an elevational view showing an end of the combined container and closure of FIG. 1;

FIG. 6 is an elevational view showing the end view opposite to the end view shown in FIG. 5 of the combined container and closure of FIG. 1; and,

FIG. 7 is a bottom plan view of the combined container and closure of FIG. 1.
